Primary Examiner — Sheryl Lane*Assistant Examiner* — Ieisha Price(74) *Attorney, Agent, or Firm* — Quarles & Brady LLP(57) **CLAIM**

The ornamental design for a link for a support assembly, as shown and described.

DESCRIPTION

FIG. 1 is an environmental top, front, left perspective view of a link for a support assembly. The broken lines shown represent the environment of the claimed design and form no part thereof;

FIG. 2 is a top, front, left perspective view of the link for a support assembly;

FIG. 3 is a front elevational view of the link for a support assembly;

FIG. 4 is a rear elevational view of the link for a support assembly;

FIG. 5 is a top plan view of the link for a support assembly;

FIG. 6 is a bottom plan view of the link for a support assembly;

FIG. 7 is a left elevational view of the link for a support assembly; and,

FIG. 8 is a right elevational view of the link for a support assembly.

1 Claim, 4 Drawing Sheets(56)
